United States Patent

Des. 237,083
Patented Oct. 7, 1975

237,083

STOVE

J. Burrell Chase, 357 Los Gatos Blvd.,
Los Gatos, Calif. 95030

Filed Aug. 10, 1973, Ser. No. 387,291

Term of patent 14 years

Int. Cl. D23—03

U.S. Cl. D23—97

FIG. 1.

FIG. 2.

FIG. 1 is a perspective view from above of a stove showing my new design.

FIG. 2 is a side elevational view thereof; the view from the opposite side is a mirror image.

I claim:

The ornamental design for a stove, as shown and described.
